IRON PLUG

Louis Ludwig, New York, N. Y.

Application April 18, 1944, Serial No. 531,623

6 Claims. (Cl. 173—332)

1

This invention relates generally to electrical connection plugs, and more particularly to electrical connection plugs for connecting pressing irons with a source of electrical energy.

Among the objects of the present invention lies the provision of electrical iron plug structure which is quickly and easily assembled or disassembled for the purpose of connecting conductors with the electrical contact elements within the plug.

Another object herein lies in the provision of structure of the class described which is operable by the use of only such simple tool or tools as are usually available to the user.

A feature of the present invention lies in the fact that the plug parts are properly manipulated by persons having relatively little skill.

In the present plug structure the plug is constituted by a plurality of plug body members which are resiliently retained in juxtaposition by the locking element. The resiliency of the locking element permits the use of the present plug with a plurality of irons in which a substantial difference in iron terminals is encountered. Thus the terminals and the body members of the plug may be temporarily displaced with respect to each other while the plug has the contact elements therein in engagement with said terminals, yet after the plug is removed from the said iron the locking element acts to urge the body members to their original positions.

Another feature of the invention lies in the fact that the body members, which together form the plug, may be of substantially identical construction so that not only do they present a symmetrical appearance but mold cost is thereby reduced and the locking element may be suitably engaged by insertion initially through either of the body members.

An important object of the present invention lies in the coaction between the locking element and the body members of the plug whereby the plug body members are maintained in predetermined spatial interrelation without the use of additional aligning means.

Another object of this invention lies in the provision of structure wherein movement of the locking elements as a unit in a single direction effects a complete locking.

These objects and other incidental ends and advantages will more fully appear in the progress of this disclosure and be pointed out in the appended claims.

In the drawings, similar reference characters

2

designate corresponding parts throughout the several views of each embodiment.

Figure 1 is a front elevational view of an iron plug showing the invention in a locked condition thereof.

Figure 2 is a fragmentary sectional view of Figure 1.

Figure 3 is a sectional view as seen from the plane 3—3 on Figure 2.

10 Figure 4 is a view in perspective of the locking element of the invention.

Turning now to the embodiment of the invention illustrated in Figures 1 to 4 inclusive, the iron plug is generally indicated by reference character 20. In a well-known manner the plug 20 may be composed of a plurality of plug body members 21 and 22. While the plug body members are of substantially identical construction for the purpose of clarity in this disclosure, the member 22 may be referred to as a front body member and the member 21 may be referred to as a rear body member. The body members 21 and 22 are of irregular configuration and as is well known may be molded of any suitable insulated material such as "Bakelite." The plug 20 may be provided with any of the well known types of electrical contact elements 18 and 19.

30 The body members 21 and 22 may thus be molded from the same mold and each of the members 21 and 22 has an outer face 23 and 24, an inner face 25 and 26, cord entrance ends 26 and 27, iron prong or contact post receiving ends 28 and 29 and irregularly shaped orifices 30 and 31, respectively. The particular shape and interwall spacing of the orifices 30 and 31 are correlated to the locking element 32 as will more fully appear hereinbelow.

40 The locking element generally indicated by reference character 32 is best seen in Figure 4, the locking element in said figure having an appearance assumed by the locking element when not under tension and removed from the plug 20.

45 The locking element 32 has a general U-shape with laterally directed extensions on the ends of the U. Thus the element 32 includes the latch element 33 which is carried by the latch element carrying portion 34. As shown in Figure 4 the locking element 32 is preferably fabricated by suitably forming two separate pieces of round 50 spring wire to take the shape there shown, and the ends of the individual wires are preferably interconnected in any suitable manner as by soldering or welding to form the terminals or tips 41 and 42. The latch element 33 therefore 55 may include the latch members 35 and 36 which

diverge from the plane in which the legs 37 and 38 lie, and from each other in the general direction of the resilient clamping fingers 39 and 40. The legs 37 and 38 preferably extend substantially perpendicularly from the ends of the portion 34. The resilient clamping fingers 39 and 40 extend from the respective ends of the legs 37 and 38 preferably at an angle of less than 90°. The tips 41 and 42 of the fingers 39 and 40 are preferably rounded so that they may have a proper sliding action upon the resilient finger receiving surfaces 57 and 59, or 58 and 60 as the case may be.

Each of the orifices 30 and 31 is preferably of a width substantially equal to or slightly greater than the width of the legs 37 and 38 and the portion 34 so that the locking element may penetrate each of said orifices. In actual practice then the distance between the wall 43 and the wall 44 may be only a few thousandths of an inch greater than the distance between the edge 45 and the edge 46 of the locking element 32. The outer faces 23 and 24 of the body members 21 and 22 adjoining the walls 43 and 44 are provided with indentations 67 and 68, and 49 and 50, respectively, which correspond with the shape and size of the latch members 35 and 36 so that when said latch members are fully seated in the indentations 49 and 50 the outermost surfaces of the said latch members are substantially coplanar or slightly below the outermost level of the outer faces 23 or 24.

The body members 21 and 22 from the ends 26-29, inclusive, extend toward each other into the orifices 30 and 31 to form the projections 53, 54, 55 and 56. Each of the projections 53-56, inclusive, has a resilient finger engaging surface 57-60, inclusive, respectively, and a leg engaging surface 61-64, inclusive, respectively.

The parts are preferably inter-related in size and position so that when the latch members 35 and 36 are in either the indentations 49 and 50 or the indentations 67 and 68, the legs 37 and 38 may have outer surfaces thereof in slidable contact with the leg-engaging surfaces 61-62, and 63-64, respectively.

The length of the legs 37 and 38 is preferably such that when the inner surfaces of the latch members 35 and 36 are in contact with the innermost surfaces of the depressions 49 and 50, or 67 and 68, the tips 41 and 42 only of the fingers 39 and 40 engage finger receiving surfaces 58 and 60 or 57 and 59, as the case may be. Thus when the body members 21 and 22 are separated from each other while the locking element 32 is in a locked position thereof, the fingers 39 and 40 may flex about the bends 65 and 66 to assume positions which are more nearly 90° or even greater than 90° with respect to the legs 37 and 38.

Operation

Assuming the parts to be completely disassembled, appropriate conductors (not shown) are connected to the electrical contacts 18 and 19 and these are seated between the body members 21 and 22 in suitably arranged depressions therefor (not shown) with the plug body members in juxtaposition as shown in Figure 2. At this point it is permissible to insert the latch element 33 into the orifices 30 and 31 in either of the body members 21 or 22; and likewise it is immaterial whether the finger 39 or the finger 40 is uppermost. Assuming, for the purpose of example, that the latch element 32 is inserted

first into the body member 21, the latch members 35 and 36 are resiliently flexed toward each other until they lie in parallel planes. This flexure is caused by the mere insertion of the latching members into the orifice 30 inwardly of the depressions 67 and 68. When the tips 41 and 42 first meet the surfaces 57 and 59 the innermost bights of the latching members will not have entered the depressions 49 and 50. This is accomplished by inserting a sharp tool such as a knife, hacksaw blade or thin screw driver first into the orifice 30 and then into the orifice 31 there to engage the said latching members so that they may be pushed outwardly of the plug (to the left as viewed in Figure 2) until said bights can snap outwardly (laterally) to engage the depressions 49 and 50 (see Figures 1 and 2).

By virtue of the construction just described it may be seen that the plug body members 21 and 22 may be separated from each other temporarily in order that they may be shifted in position to accommodate an unusual spread of the electrical contacts 18 and 19. Such movement of the body members 21 and 22 away from each other is controlled by the locking element 32 and particularly the flexure of the fingers 39 and 40 about the bends 65 and 66. It is important to note that the body members 21 and 22 may not be rotated about each other, about an axis perpendicular to the inner faces 25 or 17, a very substantial amount. This is so because of the engagement of said body members with the locking element and particularly the legs 37 and 38 thereof. The amount of axial displacement, as described, which may occur will be affected by the amount of clearance between the edges 45 and 46 of the locking element 32 and the walls 43 and 44. The bends 74 and 75 also may flex.

Upon a perusal of Figure 2 in which the plug 20 is shown in the locked and closed position thereof, it will be seen that where desired, the locking element 32 may be inserted from the left and moved toward the right so that the latch element 33 may engage the depressions in the body member 21. One of these depressions 67 is seen in Figure 2.

In order to open up the plug it is only necessary to compress or flex the latch members 35 and 36 toward each other and as soon as they are parallel with each other and can therefore enter one of the orifices 30 or 31 the bends 65, 66, 74, and 75 may become more acute and pull the latch members inwardly of the plug. The two body members may now be manually separated with ease. The last described flexure of the latch members may be accomplished by the use of any suitable tool such as a screw driver which may be inserted into the depressions let us say 50 or 49, consecutively, and since the wires which form the locking element are independent except at their ends the latch members may independently and consecutively be moved to such position as will permit the separation of the plug body members.

It may thus be seen that the present plug may be assembled and disassembled rapidly without the use of any special tools and that when in an assembled condition the parts are arranged so as to co-act with each other to properly support the electrical contacts and to articulately integrate the plug body members to provide a unitary useful electrical contact plug. In securing the plug body members in assembled relation, no threaded parts are required either in 75 the insulating material of which the plug body

members are composed or in specially fabricated threaded metal inserts. This results not only in less expensive construction but also in time saving because no screws need be inserted and turned or turned to remove. A quick snap action is obtained as the locking element is shifted from the relatively disengaged or open position thereof to the locked position thereof and vice versa.

I wish it to be understood that I do not desire to be limited to the exact details of construction shown and described, for obvious modifications will occur to a person skilled in the art.

I claim:

1. An electrical plug comprising separable plug bodies, the plug bodies having orifices aligned respectively with one another, a spring wire locking element extending through the orifices to secure the parts together, said spring wire locking element being of U-shape having legs fitting respectively opposite sides of the orifices and connected together across the orifice of one plug body by a bottom connecting portion, clamping means on the respective leg portions engageable with the plug body to limit the inward movement of the locking element and adapted to have locking engagement therewith, and means on the bottom connecting portion between the leg portions engaging the other plug body whereby to hold the plug bodies together.

2. An electrical plug comprising separable plug bodies, said plug bodies having orifices respectively aligned together, a spring wire locking element of U-shape having leg portions adapted to lie respectively at the opposite sides of the orifices, clamping fingers extending respectively from the leg portions and engaging with one plug body, a bottom connecting portion between the leg portions extending across the orifice of the other plug body, and said connecting portion having a latch formation extending out of a plane including the leg portions and engaging the other plug body, whereby to retain the plug bodies in locking engagement with one another.

3. An electrical plug as defined in claim 2, and said formation being in the form of a wire loop within the connecting portion and angled from

the plane including the leg portions to have its closed end or engaging portion at a distance from the plane.

4. An electrical plug as defined in claim 2, and said formation comprising two latching projections angled from one another and from the plane including the leg portions and from opposite sides of the plane and engageable respectively with the other body member at the opposite sides of the orifice thereof.

5. An electrical plug comprising separable plug bodies having recesses respectively aligned with one another, and a spring wire locking element comprising two U-shaped spring wires secured together in side by side relationship, each of said wires having leg portions adapted to lie respectively at the opposite sides of the orifices, the leg portions of each wire having respectively clamping fingers engageable with one plug body, a bottom connecting portion extending between the leg portions and across the orifice of the other body, said connecting portion having a loop formation therein angled out of a plane including the two leg portions and adapted to have spring engagement with the other plug body, the loop formation of one wire extending at an angle in the opposite direction from said plane than the loop of the other wire and engageable with the other plug body to the opposite side of the orifice from which the loop of the one wire engages the plug body.

6. An electrical plug as defined in claim 5, and the loops of the respective wires being at different transverse locations within the orifice.

LOUIS LUDWIG.
